The ornamental design for sunflower shaped water misting nozzle, as shown and described.

DESCRIPTION

FIG. 1 is a top planar view depicting a horizontal type embodiment of a sunflower shaped water misting nozzle in accordance with this invention shown separately for ease of illustration.

FIG. 2 is a bottom planar view of the embodiment of FIG. 1 taken near the top of the water carrying conduit leading into the bottom portion of the sunflower shaped water misting nozzle.

FIG. 3 is a side elevational view of the embodiment of FIGS. 1 and 2 showing a water misting nozzle extending slightly above a base portion of the sunflower shaped water misting nozzle.

FIG. 4 is a front elevational view depicting a vertical type embodiment of a sunflower shaped water misting nozzle in accordance with this invention shown separately for ease of illustration.

FIG. 5 is a rear elevational view of the embodiment of FIG. 4.

FIG. 6 is a side elevational view of the embodiment of FIGS. 4 and 5 showing a water misting nozzle extending slightly beyond a base portion of this sunflower shaped water misting nozzle.

FIG. 7 is an exploded side elevational view of the embodiment disclosed in FIGS. 4-6, showing the configuration of the base portion; and,

FIG. 8 is an exploded side elevational view of the embodiment disclosed in FIGS. 1-3, showing the configuration of the base portion.

In some figures the water carrying conduit is shown broken away to indicate indeterminate length.
